FILLING MEANS FOR DENTAL SPRAY BOTTLES
 Hyman Freedman, 200 W. 58th St.,
 New York, N.Y. 10019
 Filed Aug. 20, 1965, Ser. No. 481,352
 U.S. Cl. 141—353 5 1 Claim
 Int. Cl. B67c 3/28; G02b 5/08

ABSTRACT OF THE DISCLOSURE

A filling means for a dental spray bottle consisting of a hose leading from a source of liquid under pressure, the hose being provided at its end with a nippled sleeve containing a tire valve. The spray bottle has a cap provided with a radially projecting tube over which the nipple on the sleeve is fitted and the end of the tube contacts with the stem of the valve and opens the valve to cause a flow of the liquid into the cap and into the bottle to which the cap is attached.

This invention relates to dental implements, and more particularly to those of the type which are disclosed in my Patents Nos. 2,720,702 and 3,001,288. In those patents are shown dental mirrors provided with fluid-spraying means, and the present invention has reference to means for providing a spray in a certain relation to a dental mirror; to means for associating the mirror with a spray nozzle; to means for pivotally mounting the spray nozzle in company with the mirror, and to means for simplifying the filling of a spray bottle with water or other fluid.

It is an object of the invention to provide a dental mirror arrangement in which the mirror is attached, removably or permanently, to a spray nozzle, with the spray nozzle so disposed that the fluid ejected from it will be projected across the face of the mirror and substantially parallel to the plane of said face. The spray nozzle and the attached mirror are pivotally mounted between the spray tubes of the implement, thereby providing for a pivotal adjustment of the nozzle and mirror as a unit while constantly maintaining the relative positions of the mirror and nozzle with respect to one another and regardless of the position to which the nozzle and mirror unit is pivotally moved.

It is another object of the invention to provide a simplified means for filling a water or fluid receptacle to which a fluid-using dental tool, such as a mirror, is attached. In present practice, the filling of a spray bottle of the above-mentioned kind involves the unscrewing of a cap from the bottle and the filling of the bottle through its open top. The present invention contemplates the opening of a valve in a fluid-supply line by the thrust of a filler tube attached to the cap of the bottle and while said cap remains in position on the top of the bottle, so that the water or other fluid will flow into the bottle through the cap without requiring removal of the cap from the top of the bottle.

With these and other objects to be hereinafter set forth in view, I have devised the arrangement of parts to be described and more particularly pointed out in the claim appended hereto.

In the accompanying drawings, wherein illustrative embodiments of the invention are disclosed,

FIG. 1 is a front elevational view of a portion of a dental mirror holder provided with spraying means in accordance with the invention;

FIG. 2 is a side elevational view of the same;

FIG. 3 is a side elevational view of a detachable mirror;

FIG. 4 is a side elevational view of the spray nozzle

2

provided with a socket for the reception of the stem or the detachable mirror shown in FIG. 3;

FIG. 5 is a top plan view of the nozzle and attached mirror socket as seen on the line 5—5 of FIG. 4, looking in the direction of the arrows and showing the stem of the mirror in place in the socket;

FIG. 6 is a sectional view through the valve device for controlling the water or liquid flow into the container or spray bottle;

FIG. 7 shows the parts of FIG. 6 as they appear when the valve is closed but is in readiness for opening by pressure imposed on its stem by the insertion of the filler tube on the cap of the fluid receptacle, and

FIG. 8 is a sectional view, taken substantially on the line 8—8 of FIG. 6, looking in the direction of the arrows.

Referring to the drawings, and particularly to FIGS. 1 to 4 thereof, there is shown therein a dental appliance in the form of a dental mirror 1, provided at its rear with a projecting stem 2 which, in the embodiment shown in FIGS. 1 and 2, is fixedly attached to a spray nozzle 3. The nozzle may be of known form, such as shown for example in my Patent No. 3,001,288 and it is provided with an outlet or jet opening 4 which directs a fluid or water spray across the face of the mirror 1. Another outlet or jet for the fluid is shown at 6 from which a spray 7 is ejected on the tooth or area in which the dental work is in progress. The spray ejected across the face of the mirror is shown at 5.

At 8 is shown a water supply tube and 9 shows the air supply tube, these two tubes extending in side-by-side relation and are held together by means of the clamp 10. At their upper or forward ends the tubes 8 and 9 embrace the nozzle 3 between them, the nozzle and hence the mirror 1 attached thereto, being rotatively or pivotally mounted between the inturned ends 11 of the tubes 8 and 9.

The nozzle is so positioned relatively to the plane of the mirror that the spray 5 emanating from the jet outlet 4, is directed substantially parallel to and across the face of the mirror to cleanse the same, since the outlet end of the jet opening 4 is located close to the peripheral edge of the mirror and is so directed that it directs its spray across the face of the mirror.

By means of the disclosed arrangement, the mirror and the nozzle, being secured together as a unit, are maintained as a unit in a specific relationship so that the spray emanating from the nozzle is constant as to direction in relation to the mirror. The unitary pivoting of the mirror and nozzle permits the mirror to be swung to any desired position required for the work being performed and with the assurance that the spray emanating from the nozzle will always be best directed for not only cleaning the mirror but for also cleaning the seat of dental operations.

In the embodiment of FIGS. 1 and 2, the mirror is shown as being permanently attached to the rotative nozzle. In FIGS. 3 and 5 the stem of the mirror is shown as being removably fitted within a socket 12 that is fixedly attached to the nozzle. As seen in FIG. 5, the socket may be in the form of a split ring and it frictionally engages the stem 2 of the mirror with sufficient gripping force to hold it from both longitudinally shifting or becoming rotatively displaced.

In FIGS. 6 to 8 inclusive is disclosed an arrangement for filling a fluid container, such as the water bottle or similar receptacle that is used in connection with such dental appliances which spray water or other fluid, such as for example, the mirror appliance shown in FIGS. 1 to 5. In this arrangement, the water and air tubes 8 and 9 respectively enter into a head 13 which is rotatively mounted in a cap 14 threadably received in or on top of a

ferrule 15 secured by cement or otherwise to the top of a bottle 16 or similar container as used on a dental tool.

The cap 14 carries a siphon tube 17 which extends into the bottle and the water 18 or other fluid is drawn upwardly in the usual manner through the tube 17 for expulsion out of the spray outlets 4 and 6 as shown in FIG. 2.

One of the objections encountered by the dentist in using an arrangement of this kind is the procedure involved in filling the bottle. This requires the unthreading of the cap 14 and its removal from the top of the bottle; the pouring of the water into the bottle and then the replacement of the cap. The present invention contemplates the elimination of this method of filling the bottle.

Fixed in and extending through the ferrule 15 is a tube 19 which has a part projecting into the ferrule above the top of the bottle neck, and has another part, shown at 19a located on the outside of the ferrule and projecting radially from the same.

The bottle-filling device includes a flexible tube connected to and extending from a source of water or other fluid to be delivered into the bottle. The tube is fitted at its outlet end with a sleeve 22, which is internally threaded to receive a valve 23. The valve 23 may be any one of numerous types and that which is illustrated in FIG. 5 and found satisfactory for the purpose is the widely used tire valve. Such a valve used in millions of automobile and bicycle tires includes a stem 24 which when depressed, will cause the opening of the valve and will hold it open as long as the pressure is maintained on the stem 24.

Provided in the free end of the sleeve 22 is a tubular nipple 25 which serves as a guide for the portion 19a of the filler tube 19. The bottle-filling procedure is a simple one since it consists in merely inserting the part 19a of the filler tube 19 into the guide nipple 25 and by such insertion causing the end of the part 19a to come into contact with the end of the stem 24 and depress said stem to thereby open the valve 23. The water or other fluid under pressure is forced through the tubing 21 from its source, and which water might be that obtained from a tap, and will be forced through the sleeve 22, past the open valve 23 and will flow through the filler tube 19 to enter and fill the bottle. Thus, when the bottle needs filling, the dentist need not interrupt his work for a substantial period such as that required to fill the bottle in the usual way, but need only depress the valve stem 24 by the push of the tube 19 against it to secure a flow of the water into the bottle. The valve will, of course, close to shut off the water flow upon the cessation of the pressure by the tube 19 on the stem 24.

While I have herein mentioned the described device as being applicable for the filling of the bottle with water, it can be used for the supply of air, or valves of the kind described can also be used for the supply of carbon dioxide or other compressible gas. Valves of the kind described can be used in pairs or in multiple to interchangeably supply air or water or both. Also, while I have described the receptacle 16 as being a bottle, the same might be a bulb or flexible bag or other suitable container.

While I have herein described embodiments of the invention, it is obvious that the same is not to be restricted to the specific arrangements disclosed, but is broad enough to cover all structures coming within the scope of the annexed claim.

What I claim is:

1. A filling device for the spray bottle of a dental implement, the bottle having a cap provided with means for fitting it on the top of such a bottle, a fixed filler tube extending radially through the cap above the mouth of the bottle on which the cap is fitted, said tube having a portion located and exposed on the outside of the cap, a fluid-supply conduit terminating in a sleeve containing a normally closed valve having a valve stem which, when depressed by contact with the end of the exposed part of the filler tube, will cause opening of the valve, a guide nipple on the end of the sleeve for slidable fitment over the exposed part of the filler tube to cause the valve stem to be guided into contact with the end of the filler tube by the slidable movement of the nipple over the exposed part of the filler tube and cause opening of the valve to provide the flow of fluid past the valve and through the filler tube to enter the bottle.
